H. A. W. WOOD.
INSERT PRINTING PRESS.
APPLICATION FILED JAN. 31, 1919.

1,392,469.

Patented Oct. 4, 1921.

UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

INSERT-PRINTING PRESS.

1,392,469.

Specification of Letters Patent.

Patented Oct. 4, 1921.

Original application filed September 7, 1910, Serial No. 580,870. Patent No. 1,232,639, dated July 10, 1917. Divided and application filed June 29, 1917, Serial No. 177,652. Divided and this application filed January 31, 1919. Serial No. 274,217.

To all whom it may concern:

Be it known that I, HENRY A. WISE Wood, a citizen of the United States, residing at New York, in the county of New York and 5 State of New York, have invented a new and useful Insert-Printing Press, of which the following is a specification.

This is a division of my application for patent, Serial No. 177,652 filed June 29, 10 1917, which in turn is a division of my Patent No. 1,232,639 granted July 10, 1917, on a machine for making magazines and the like, filed September, 7, 1910, Serial No. 580,870.

15 This invention relates to the art of printing books, magazines, and newspapers which are made up of several signatures varying in character of paper and number of pages, together with inserts of one or more leaves.

20 The principal objects of this invention are to provide an organized mechanism for the purpose of printing the inserts in colors; to provide a practicable and efficient form of printing press for making the inserts and to provide for great flexibility in the order and arrangement of the products of several presses, so that signatures can be introduced into the magazine in any desired order to save space, and a further object is 25 to reduce labor and expense. The invention 30 also involves several improvements in combinations of parts and details of construction, particularly in the insert press as will appear hereinafter.

35 Reference is to be had to the accompanying drawings, in which—

Figure 1 is a diagrammatic side view of a machine constructed in accordance with this invention for printing and feeding an insert and associating it with the sheets, and 40

Fig. 2 is an enlarged view of the folding and connected mechanism shown in Fig. 1 but somewhat modified.

In the drawings a machine is shown for 45 printing the inserts in which they can be printed in a plurality of colors on one side of the web. It will be understood of course that by a similar arrangement color printing on both sides can be done. The insert web 50 W is drawn from a reel 30 over web rolls 31, over a large impression cylinder 29 or a plurality of small impression cylinders 21, 41 of an insert press G as desired, printed by

the several plate cylinders 20, 40 in a well known way, slit at D, cross-associated by the 55 turning bars 51, and the several webs w^1 , w^2 , w^3 and led to cutting devices 32 and finally associated on a gathering device R with the product of the main high speed press A' cut up by cutting devices F. If it is desired to 60 print on both sides of the insert web w it is led through the insert press as shown in dotted lines at the right of Fig. 1. In this case the plate cylinder 40 is movable so as to contact with either of two impression 65 cylinders 41 or 42. Two ink fountains 43 and 44 are shown for two colors of ink. When the plate cylinder is shifted the inking mechanism 45 can be shifted also as shown in dotted lines. 70

The cutting devices 32 shown here preferably operate as follows: A grooved cutting cylinder 5 is used with a knife cutting cylinder 6 having two knives 7 when two page signatures are desired. For the web 75 w^4 another cutting device 36 is shown having one knife. For four page signatures the cutting cylinder 6 is moved out of operation and the cylinder 60 having one knife is moved into operative position. For signatures of four, eight, or sixteen pages the collecting is done on the knife cutting cylinder 6. 80

The sheets are nipped by the drop rolls and advanced by the tapes 35 which carry 85 them to a cylinder 37. This cylinder has pins or grippers 38 for receiving the sheets and carrying them around so as to transfer them to a cylinder 39, which folds and transfers them to the gathering drum R. This 90 applies to all but two-page signatures which are transferred to the drum R from the cylinder 37 by a cylinder 34.

If tissue t is desired with the inserts it is 95 drawn from a roll g^6 cut into sheets on a cylinder g^7 fed between tapes g^8 and pasted with a line of paste. This is done by a paste blade g^9 which moves to and from a paste roll g^5 . The sheets are carried by the tapes to the cylinder 39 where they meet the signatures as indicated. 100

The insert press G can be arranged to carry eight plates around the cylinder, and four or less along it. With this device running at the same speed as the main press, 105 arranged four plates wide and with four

collecting devices it will furnish sixteen, eight, four, two or one signatures, having respectively four, eight, sixteen, thirty-two or sixty-four pages. In the first case there will be no collection, in the second one, and in the other cases three. When the cylinder is run with a less number of plates in width, and a less number of collecting devices, the number of signatures and pages will be restricted in proportion. Running at one-half the speed of the main press this press will furnish the same number of signatures of one-half the number of pages and one-half the number of signatures of the same number of pages as for full speed, and corresponding reductions will be made when running at one-quarter of the speed of the main press, and at an eighth, sixteenth, or less. When running one-thirty second the speed of the main press it will furnish one two-page signature. It will be seen that by this construction, one is enabled to supply to a fast running press sheets, such as frontispieces or inserts, which are being simultaneously printed but at a very much lower rate of speed. To take one of the examples given above, supposing the press G is two pages wide and eight in circumference; that is, having sixteen plates on the cylinder all duplicates, it will deliver sixteen products at each revolution. These products may be fed to the gathering drum R with the product of another press which is running sixteen times as fast, and will supply the gathering mechanism with a product for each product of the other press. That is, in this case if the press A' is running sixteen times as fast as this press G, one product of each will be fed to the gathering drum R at the same time. In this way the presses for the ordinary work can be speeded up as much as necessary, and yet the presses for the color work and other particular parts can be run at such a low speed that the product can be made with a very high degree of excellence. With the feeding devices shown it is obvious that the circumferential products of the press G will follow each other, as is usual with a press which does not collect, by means of this distributing mechanism. All the lateral products of the press as well are turned into the same stream so that the entire product will be delivered in a series, one after the other, to the large gathering drum, a single product for each turn, thus both the lateral and circumferential products of the press are distributed in sequence. In this way it will require sixteen turns of the drum in order to exhaust the products made by one turn of the press. At the same time, the drum is collecting the products of sixteen revolutions of the press A' turning out ordinary work. It will be understood of course that if desired the collating device can be ar-

ranged so that the product of this press will be run out in two streams instead of one, in which case this press must run at one-eighth of the speed of the other press A', if that turns out one product per revolution. Supposing this to be applied to a newspaper press of the present style, which is turning out a Sunday paper at the rate of 24,000 an hour, and which prints two products to a revolution, the addition of this press to the newspaper press would result in supplying a colored insert for every paper, and yet the speed would be only one-eighth of that of the news press or one-sixteenth if applied to a press of another type turning out only one produce for each revolution. It is obvious also that the width of this machine can be increased within the scope of this invention so as to produce five products in width or any other practical number and that the speed will then be reduced proportionately. Similar results can be obtained with the other insert presses or feeders shown in Fig. 1.

While I have illustrated and described several preferred modifications of the invention and of different parts thereof, I am aware that many other modifications can be made even in those parts which have been illustrated in several forms, and that as far as most of the features of the invention are concerned, they do not depend upon the details of construction. Therefore I do not wish to be limited to any particular type of the various machines or elements of the plant or mechanism described or to the other details of construction shown, except as expressed in the claims, but what I do claim is:—

1. In a machine of the character described, the combination with a printing press or deck, and means for feeding the products of said press or deck, of an insert press constructed and adapted to produce a plurality of duplicate products at each revolution, means for slitting the web from said insert press to form a plurality of narrow webs, means for cross-associating said narrow webs, means for cutting up each of said narrow webs into sheets, means for receiving one sheet from each of said narrow webs, the insert press comprising a plate cylinder, an impression cylinder on each side thereof at a greater distance apart than the length of the diameter of said cylinder, two inking fountains, and an inking device adapted to coöperate with either of said fountains and with said plate cylinder, whereby the web may be led through the same in two different ways to be printed on opposite sides. 105

2. In a machine of the character described, the combination of an insert press constructed and adapted to produce a plurality of duplicate products at each revolution, means for slitting the web from said 110

insert press to form a plurality of narrow webs, means for cross-associating said narrow webs, means for cutting up each of said narrow webs into sheets, the insert press comprising a series of plate cylinders, one of said plate cylinders being movable into two positions, an impression cylinder on each side thereof at a greater distance apart than the length of the diameter of said cylinder, 10 two inking fountains, and an inking device adapted to coöperate with either of said fountains and with said plate cylinder, whereby the web may be led through the same in two different ways to be printed on 15 opposite sides.

3. In a printing press, the combination with a series of plate cylinders comprising a plate cylinder movable into two positions, and two impression cylinders for the last 20 named plate cylinder, each adapted to contact therewith when it is in one of its extreme positions, of two ink fountains, and an inking device adapted to coöperate with either of the fountains and deliver ink to the 25 said last named plate cylinder in each of its positions.

4. In a printing press, the combination of a plate cylinder movable into two positions, two impression cylinders, each adapted to 30 contact therewith when it is in one of its extreme positions, two ink fountains, and an inking device adapted to coöperate with either of the fountains and deliver ink to said plate cylinder in each of its positions.

35 5. In a printing press, the combination of a plate cylinder movable into two positions, two impression cylinders, each adapted to contact therewith when the plate cylinder is in one of its extreme positions, two ink fountains, an inking device adapted to coöperate with either of the fountains and deliver ink to 40 said plate cylinder in each of its positions, and means for guiding a web between the said plate cylinder and either one of the 45 impression cylinders, whereby the web may be printed upon either side and different

webs may be printed on in different colors on opposite sides.

6. In a machine of the character described, the combination of a cylinder having means thereon for receiving a plurality of sheets around it, a plurality of means for delivering to it, a folding cylinder for receiving signatures therefrom and folding them, a gathering device, and means for transferring the signatures to the gathering device.

7. In a machine of the character described, the combination with a printing press or deck, a gathering device, and means for feeding the products of said press or deck to the gathering device, of an insert press constructed and adapted to produce a plurality of duplicate products at each revolution, means for cutting up the several insert webs into sheets, and means for transferring said sheets from a plurality of insert webs one at a time to the gathering device comprising a gripping cylinder.

8. In a machine of the character described, the combination with a gathering device, of a low speed insert press provided with means for printing on either side of an insert web, means for slitting the insert web, means for cutting up each strand of the slit web to form a plurality of inserts, a high speed press arranged to run as many times as fast as the insert press, as the insert press prints duplicate products per revolution, and means for delivering a single product of each press to the gathering device in the same length of time.

9. In a machine of the character described, the combination of two impression cylinders spaced apart, a plate cylinder movable into contact with either one of them to coöperate therewith, and an inking device adapted to deliver ink to said plate cylinder in each of its extreme positions.

In testimony whereof I have hereunto affixed my signature.

HENRY A. WISE WOOD.
